UNITED STATES PATENT OFFICE.

AUGUST DWORAK, OF STUTTGART, GERMANY.

PAMPHLET-COVERING MACHINE.

1,141,785.

Specification of Letters Patent. Patented June 1, 1915.

Application filed August 20, 1913. Serial No. 785,795.

To all whom it may concern:

Be it known that I, AUGUST DWORAK, a subject of the King of Wurttemberg, residing at 3 Pfitzerstrasse, Stuttgart, Wurttemberg, in the Empire of Germany, have invented certain new and useful Improvements in Pamphlet-Covering Machines, of which the following is a specification.

The present invention relates to a machine for covering pamphlets, loose sheets or signatures of paper.

The main object of the invention is to provide a machine which will turn out covered pamphlets and the like which are durable and of good appearance.

The improvements relate mainly to the mechanism for applying the adhesive and to the mechanism for applying the cover around the block of sheets and pressing it thereon. In this machine the covers are conducted singly by an automatic device or by hand to a creasing device in which channels are formed in the cover so that when the latter is subsequently applied to the block of sheets there are sharp edges between the back and the sides; thence the covers pass to a gluing device where an adhesive substance is applied to their back portions. From the gluing device they pass to the covering mechanism. This consists of a revolving member rotatable about a vertical pivot and provided with clamping means in which the loose blocks of sheets are placed and by which they are carried, in a half-revolution, over the glued cover. During the half-revolution of the revolving member the block of loose sheets is carried over a gluing device and coated with glue on the back. When a block of sheets clamped in the clamping device of the revolving member is located above the cover, the latter is raised by a vertically reciprocating clamping device and firmly applied to the block of sheets. The clamping device of the revolving member then releases the block of sheets and the finished pamphlet remains clamped in the reciprocating clamping device. By means of this clamping device it is carried to a collecting or depositing box in which the finished pamphlets are collected and pressed together for a certain time.

Figure 1 shows the machine as a whole in elevation, partly in section. Fig. 2 is a plan view of Fig. 1. Fig. 3 is a fractional eleva-

tion, partly in section, on the line A—A of Fig. 1, seen in the direction of the arrows, and showing the general arrangement of the revolving member feeding the blocks of sheets to the covers, and of the vertically reciprocating mechanism for applying the covers to the blocks of sheets and for depositing the covered pamphlets in the collecting box. Figs. 4 and 5 are respectively a side elevation and a front elevation of the device for applying adhesive to the covers on the line B—B, of Fig. 1. Fig. 6 illustrates one of the clamping devices of the revolver in sectional elevation shown in Figs. 2 and 3. Fig. 7 is a front elevation on the line C—C of Fig. 3 of the clamping device applying the covers around the block of sheets, several parts being broken away. Fig. 8 is a plan view of the clamping jaws of the reciprocating device shown in Fig. 7 on the line D—D of Fig. 7. Fig. 9 is a section of the clamping jaws shown in Fig. 8. Fig. 10 is a side elevation of the clamping jaws shown in Fig. 7. Fig. 11 is an underneath view on the line E—E of Fig. 7 of the device for locking the plate pressing against the back of the pamphlet. Figs. 12 and 13 are respectively a front elevation and a side elevation on line F—F of Fig. 7 of the device for prizing apart the clamping jaws shown in Fig. 7. Figs. 14 and 15 are respectively a front elevation and a plan of an adhesive applying device which is used for very thin pamphlets. Fig. 16 is a side elevation of the locking mechanism for the rotating member; Fig. 17 is a side elevation of the movable clamping jaws of the vertically reciprocated mechanism for applying the covers to the pamphlets showing operative and inoperative positions of guide flaps. Fig. 18 is a front elevation of the clamping jaws and guide flaps shown in Fig. 17.

The covers are placed in a pile upon the table 1 so that their inner side lies upward. From this pile they are brought separately either by hand or by any suitable mechanism, between feed rollers 2 and 3 with their inside face upward with one top edge leading. The lower roller 2 is continuously driven so that it runs uninterruptedly in one and the same direction, while the upper roller 3, which is not positively driven, can be raised and lowered, this being effected by means of a rod 4 by which it is supported

and a cam 5 which acts on one end of an intermediate lever 6. After the passage of each cover the roller 3 is raised and only lowered again by springs 7 after the introduction of the next cover between the two rollers. By means of the feed rollers the covers are carried at uniform intervals of time to and between the continuously rotating channeling or creasing rollers 8 and 9, 10 by means of which two creases or grooves are impressed in the cover. These creases serve the purpose, when the covers are being applied around the pamphlet to produce a sharp and clear bend between the 15 back portion and the sides, thereby imparting a good appearance to the pamphlet.

The gluing roller 10 (Figs. 4 and 5) is arranged behind the creasing rollers and applies the glue or adhesive to the back portion 20 of the cover. The gluing roller 10 is also driven continuously. From the glue tank 11 the gluing roller 10 is provided with glue by the intermediary of the roller 12 mounted in the tank 11 and also continuously 25 driven. The glue tank is fixed to the rod 4 and is therefore raised and lowered simultaneously with the upper feed roller 3, the positions of the rollers 10 and 12 being such that it is only when the glue tank is raised 30 to its highest position that the roller 12 contacts with the gluing roller 10, while at other times there is a clear space between them so that the covers, which, in consequence of the periodical action of the feed 35 rollers 2 and 3, can only be carried beneath the gluing roller 10 when the glue tank 11 is lowered are not coated with glue upon their outside. Beneath the gluing roller 10 and on both sides thereof springs 13 are arranged. By means of these springs when 40 the covers pass beneath the gluing roller 10 they are pressed against it so that the glue is deposited uniformly upon the covers from the roller. The advantage of this gluing 45 device is that the periphery of the gluing roller need not correspond with the length of the cover, so that one gluing roller can be used for covers of different lengths, while soiling of the outside of the cover with glue 50 is completely prevented. The glued covers then pass from beneath the roller 10 to the conveyer bands 14. On the one hand these bands run over a roller 15 behind the roller 10 and on the other hand over rollers 16 at 55 the end of the machine and then around rollers 16^a (Fig. 2) and are kept permanently taut by means of weights 17 hung on the spindle of these rollers. The roller 15 is driven so that it always runs in one direction. The drive of the lower feed roller 2 the channeling rollers, the gluing roller and the rollers 12 and 15 is effected from the driving shaft 18, through a chain 19 driving a wheel 20, from which the said elements 60 are driven by means of gear wheels 65

21. The covers are conveyed by the conveyer bands until their travel is arrested by stops 92 (Fig. 2). In the meantime the block of sheets which are to form the pamphlet is inserted in one of the two 70 clamping devices of the revolver (Figs. 3 and 6) and by a semi-revolution of the revolving member are brought over the cover conveyed by the bands 14.

The revolver consists of two pairs of 75 clamping jaws 23 and 24 rotatable about a vertical shaft 22 and diametrically opposite each other. The outer clamping jaws 23 are carried by arms 25 upon which they are adjustable by means of set screws 30, in 80 order to modify the distance between the outer and inner jaws to correspond with the thickness of the pamphlets to be dealt with. The inner jaws 24 are fixed to pivots 26 (Fig. 6) displaceable radially to the shaft 85 22 in the hollow sleeves 27. Springs 28 tend to press the pivots 26 and jaws 24 outward so that the block of sheets is clamped between the jaws 23 and 24. Rollers 29 are secured to the pivots 26 and serve to draw 90 back the inner jaws 24 for the purpose of inserting the block of sheets and releasing it again after the cover has been folded over the sheets. The rollers 29 engage in a cam 95 path 31 in a guiding frame 32 which is constructed and operates in the following manner: The frame has the shape of the dome of a bell which has been vertically cut through so as to leave a little more than half the dome. In the interior of this dome at 100 its lower edge is formed a cam path for the rollers 29 actuating the movable jaws 24, the cam path being so formed as to pull the jaws 24 apart from the jaws 23 against the action of the spring 28. The dome 32 is 105 rotatable on the vertical shaft 22. The revolver is driven from a cam 33, mounted on the same shaft as the cam 5. This cam rocks a lever 34, the movement of which is transmitted through a rod 35 and arm 36 to a 110 shaft 37 (Figs. 1 and 2). The shaft 37 transmits the movement through bevel pinions 38 Fig. 3 to a shaft 39 from which the hollow sleeve 27 carrying the clamping jaws is intermittently rotated through 180° at 115 each operation by ratchet gear 40, while by means of projections 55 acted on by suitable mechanism the dome 32 is displaced so that the jaws, between which the stack of sheets has been inserted above the table, are caused 120 to close before they commence their rotatory movement, and after they have rotated through 180° and the cover has been laid around the sheets they open, before they continue their rotation around the shaft 22. 125 On their under side the outer jaws 23 are provided with notches 42 and upon the inner jaws 24 thin plates 43 are hinged (Fig. 6), their lower edge which projects below the lower edge of the jaws 24 being also 130

provided with notches 44, and which register with the notches 42 in the clamping jaws 23. The purpose of this device is hereinafter explained.

5 The revolving member is exactly adjusted after each semi-revolution by means of a locking device (Fig. 1) which retains it firmly until another rotation takes place. This locking device consists of a bolt 93 displaceable upward and downward in the machine; a spring 94 tends to press or draw it upward so that when it comes opposite a corresponding notch in the revolving member it engages therein. The bolt and the 10 notches are wedge-shaped so that even if the revolving member is not quite exactly positioned the bolt will pass into the notch and is therefore able to rotate the revolving member into the exact position.

15 A rack is arranged upon the bolt and a toothed segment on the end of a lever 95 meshes therein. The lever 95 is displaced upward and downward by a cam plate 110 (Fig. 2) by means of a rod 96, whereby the 20 bolt is withdrawn from the notch at the proper moment so that the revolving member can continue its rotation.

A pair of clamping jaws 45 (Figs. 7 to 30 13) serve to apply the cover to and press it against the block of sheets to be covered. The clamping jaws 45 are arranged upon a cross-member 46 guided by the rods 47 and displaceable vertically. This vertical reciprocation causes the lower jaws 45 to 35 come alternately directly beneath the jaws 23, 24 of the revolving member in order to provide with its cover the block of sheets carried past by the revolving member, to seize it and deliver the finished pamphlets 40 opposite the collecting box. The upward and downward movement of the cross member 46 is produced by a cam plate 48, movement being transmitted therefrom by a rocking lever 49 with a sector 50 engaging 45 toothed wheels 51 and 52 which mesh with a rack rod 53 rigidly connected with the cross member 46. The clamping jaws 45 are rotatably mounted upon the cross member 46 by means of the parallel shafts or 50 hinges 54. Levers 56 are secured to the outer ends of each shaft 54. These levers are rigidly connected with the jaws 45 by means of screws 58 (Fig. 10). Between the two levers on each side a spring 57 is ex- 55 tended and tends to draw together the two levers and with them the two jaws 45, so that a pamphlet clamped between the jaws is held by a spring power until this is overcome by some other force. This renders it possible 60 to maintain the finished pamphlet between the jaws until they have conveyed it to the collecting box. On their upper edges the jaws 45 are provided with serrations 62 which are so arranged that they engage be- 65 tween the notches 42 and 44 on the upper

jaws 23 and 24 when the lower jaws co-operate with the upper. Between the two jaws 45 is a plate 59 carried by pins 60 vertically displaceable in the cross member 46. Springs 61 press the pins 60 and the 70 plate 59 upward. The plate 59 serves to press the cover against the back of the block of sheets so that the latter will adhere to the cover throughout its length. Accordingly when a pamphlet is clamped in the 75 jaws 45 the springs 61 must first of all be compressed by pressure exerted by the back of the pamphlet upon the plate 59. In order that the springs 61 may not prematurely force the pamphlet out of the jaws 45, a 80 locking device (Fig. 11) is provided. This consists of a plate 63 displaceably arranged on the under side of the cross member 46. Screws 64 passing through slots 65 hold this plate in position and bolts 66 arranged upon 85 it engage heads 67 upon the ends of the pins 60 which protrude below from the cross member 46. By this means the pins 60 and the springs 61 are prevented from being pressed upward higher than is necessary for 90 the heads 67 to encounter the bolts 66, whereby the travel of the plate 59 between the clamping jaws 45 in the upward direction is limited. Springs 68 engage the plate at one end, their other ends being fixed to 95 the cross member 46 thereby tending to press the plate laterally to such an extent that the bolts 66 engage the heads 67. A nose 69 is also provided on the under side of the plate 63. When the cross member 46 100 105 with the jaws 45 assumes the lowest position, the nose 69 encounters a pin 70 fixed to the frame of the machine. By this means the plate is displaced laterally in opposition to the tractional effort of the springs 68 and the bolts 66 are pressed behind the heads 67, so that the springs 61 are able to press upward between the jaws 45 the pins 60 with the plate 59 fixed thereon.

Devices are arranged upon the machine 110 frame for opening the jaws 45 in their highest and lowest positions; these devices penetrate between the levers 56 connected with the jaws 45 and thereby prize apart the said jaws.

The upper device (Figs. 12 and 13) consists of a wedge-shaped nose 71 fixed to one end of a lever 73 rocking about a bolt 72. A spring 74 engages the other end of the lever 73 and draws this end of the lever 120 downward. Owing to the fact that the lever bears upon the surface 75 its movement in this direction is limited. When the jaws 45 move upward, the nose 71 penetrates between the two levers 56 and as it is unable to yield relatively to the surface 75, it prizes the levers 56 apart. As soon, however, as the noses 76 on the levers 56 have passed over the nose 71, the levers 56 again snap together with the jaws 45 secured to them, 125 130

under the influence of the springs 57. At the lower end of their travel the jaws 45 are opened by the wedge-shaped pin 76 fixed to the frame of the machine, this pin penetrating from below between the levers 56 when the jaws move downward. Finally means are provided for limiting the travel of the plate 59 on the revolver. In order to prevent the plate 59 from being pressed too high by the springs 61 when it is applied against the block of sheets still clamped in the revolving member, which might readily happen in the case of very thin pamphlets whereby the sheets, as soon as they project from the jaws 23, 24 of the revolving member would be bent over, pins 77 are arranged upon the revolving member upon either side of the jaws 23 and 24, the plate 59 pressed upward by the springs 61 bearing against these pins whereby its travel is limited.

Beneath the revolving member a gluing device is provided (Figs. 1 and 2) by means of which the block of sheets clamped in the jaws of the revolving member are coated with glue on the back portion. This gluing device consists of a glue tank 78 in which a roller 80 continuously driven by a cord and pulley device 79 is mounted. Above the roller 80 is a second roller 81, which contacts with the roller 80, by which it is consequently driven and also supplied with glue. The back of the block of sheets clamped in the jaws 23, 24 slides over this roller 81 when owing to the rotation of the revolving member it is carried from the supply table 41 toward the interior of the machine.

The ejecting device consists of a plate 82 fixed to one end of a rod 84 displaceably mounted in a sleeve bearing 83. A bell crank lever 85 engages the other end of the rod 84, and is operated from a cam plate 86, whereby the reciprocation of the rod 84 is effected. As soon as the jaws 45 with a finished pamphlet have reached their lowest position and the jaws 45 have been opened by the pin 76, the plate 82 presses the pamphlet into the collecting box 87. In order to prevent the pamphlets from falling out laterally, flaps 88 are arranged rotatably on pins 89 on each side of the ejecting device. When the jaws 45 move downward, the roller 90 encounters a stop 91 on the cross member 46 and by this means the flaps 88, which are normally turned back, are raised and come upon both sides of the pamphlet, so that it is unable to escape laterally during its ejection.

The operation of the machine is as follows: After a cover has been introduced between the feed rollers 2 and 3 it is creased by the rollers 8 and 9 and glued by the roller 10. It is then carried by the conveyer bands 14 to the stops 92. At the same time 60 a block of sheets has been inserted in the

clamping jaws 23, 24 located above the supply table 41 in such a manner that its back projects very slightly below the serrations 42, 44, and after the jaws 23, 24 have carried the clamped block over the gluing roller 70 81 in the rotation of the revolving member, it comes above the cover which is retained by the stops 92. At this moment the cross member 46 with the jaws 45 moves upward whereby these jaws are prized apart by the 75 nose 71 before they reach their highest position. The plate 59, located between the jaws 45 is able to move upward as it is not locked, and it presses from below against the cover, which is thus pressed against the 80 back of the block of sheets clamped in the revolving member. In the following short further upward movement of the cross member 46, the plate 59 encounters the pins 77 so that it is unable to follow the continued upward movement of the cross member and its pressure against the back of the pamphlet cannot become excessive. As the springs 61 are compressed and the pins 60 depressed, the heads 67 of the pins 60 come 90 beneath the bolt 66 and the springs 68 are therefore able to shift the plate 63 laterally, so that the bolts 66 engage the heads 67 and thus lock the plate 59. Before the cross member 46 with the opened jaws 45 reaches its highest position, the two jaws 45 apply the cover around the block of sheets still clamped in the revolving member and, at the moment at which they reach their highest position, the levers 56 snap together again over the nose 71 so that the jaws 45 now press the cover onto the block from both sides. The serrations 62 engage the serrations 42 and 44 and the pamphlet is simultaneously clamped in the jaws 23, 24, 105 on the revolving member and in the jaws 45. By this means the blocks of sheets are prevented from becoming disarranged during the covering operation. As soon as the lower jaws 45 have seized the pamphlet, the upper jaws are opened; this is effected owing to the fact that, by a rotation of the bell 32, the roller 29, rigidly connected with the jaws 24 is moved by the cam path 31, to draw the inner clamping jaw 24 inward. 110 This causes the plate 43 carrying the serrations 44 to separate from the jaw 24 and set itself obliquely (Fig. 6). In this position it is withdrawn from the pamphlet upon the further inward movement of the 120 inner clamping jaw 24, without injuring the cover. The cross member 46 with the pamphlet clamped in the jaws 45 then moves downward. Shortly before the lowest position is reached the pin 76 penetrates 125 between the levers 56 and opens the clamping jaws 45. Immediately thereafter the nose 69 encounters the pin 70 thereby releasing the plate 59 which owing to the action of the springs 61 lifts the pamphlet 130

over the jaws 45 so that it can now be pressed by the plate 82 into the collecting box 87.

The machine can also be employed for covering single sheets. In this case the back is too narrow to enable the cover to be glued in the manner above described, so the glue is applied to the sheet laterally. With this object the gluing rollers 80, 81 are removed and the device illustrated in Figs. 14 and 15 substituted. The plates 43 are also removed from the jaws 24. The sheet clamped in the jaws 23, 24 is therefore exposed upon its inner side, so that it can be coated with glue while it is clamped. The apparatus for applying the glue consists of a gluing wheel 97 rotatable about a vertical shaft. When the revolving member rotates, this gluing wheel travels laterally upon the clamped sheet which is prevented from escaping by the serrations 42 of the outer clamping jaw 23. As the sheet occupies different distances from the axis of rotation of the revolver, in order that the gluing wheel 97 may contact with it throughout its entire length, this wheel must be displaceable radially to the axis of rotation of the revolving member. With this object it is mounted upon a carriage 98 running on rails 100 by means of rollers 99. By means of a weight upon the cable 101 the gluing wheel is kept in contact with the sheet to be glued. The wheel 97 is driven by cord transmission acting on the roller 102. This roller is fixed to a shaft 103 which also carries a gear wheel 104. The latter meshes with a long or thick wheel 105 mounted on the carriage and which is displaced upon the wheel 104 when the carriage is reciprocated. A shaft 106 to which the wheel 105 is keyed drives the shaft 108 of the wheel 97 by bevel gearing 107. The glue is applied to the wheel 97 from the glue tank 111 by a roller 109.

45 What I claim and desire to secure by Letters Patent is:—

1. A machine of the class described comprising in combination feeding rollers for the covers, means for applying glue to the inside of said covers, rollers for grooving said covers, a rotating member for delivering blocks of sheets to the covers having movable serrated clamping jaws, means for applying the cover to the block of sheets, movable jaws carried by said means and serrated along their edges, said serrations engaging between the serrations on the jaws of the rotating member, substantially as described.

60 2. A machine of the class described comprising in combination feeding rollers for the covers, a gluing device for applying glue to the inside of said covers, rollers for grooving said covers, a rotating member having movable jaws of which one is ser-

rated along its lower edge and the other is provided with a plate hinged thereto and serrated along its lower edge, a device for applying the cover to the block of sheets, movable jaws carried by said device and 70 serrated along their edges, said serrations engaging between the serrations on the jaws of the rotating member substantially as set forth.

3. A machine of the class described comprising in combination feeding rollers for the covers, a gluing device for applying glue to the inside of said covers, grooving rollers for said covers, a rotating member having movable jaws of which one is serrated along 75 its lower edge and the other is provided with a plate hinged thereto and serrated along its lower edge, a vertically reciprocated device for applying the cover to the block of sheets, movable jaws carried by 80 said device and serrated along their edges, said serrations engaging between the serrations on the jaws of the rotating member, and stops for prizing apart the said movable jaws of the vertically reciprocated device 85 shortly before they reach their highest position and as they reach their lowest position, substantially as set forth.

4. A machine of the class described comprising in combination feeding rollers for 95 the covers, a gluing device for applying glue to the inside of said covers, rollers for grooving said covers, a rotating member having movable jaws of which one is serrated along its lower edge and the other is 100 provided with a plate hinged thereto and serrated along its lower edge, a vertically reciprocated device for applying the cover to the block of sheets, movable jaws carried by said device and serrated along their 105 edges, said serrations engaging between the serrations on the jaws of the rotating member, a stop for prizing the movable jaws of the vertically reciprocated device apart shortly before they reach their highest position, consisting of a lever mounted in the path of travel of said jaws and so as to be incapable of motion in an upward direction but capable of movement in a downward direction, whereby the movable jaws are 110 prized apart as they move up, snap together over said stop, and move downwardly in closed position, and a stop for prizing said jaws apart as they reach their lowest position consisting of a wedge-shaped projection, substantially as described.

5. A machine of the class described comprising in combination feeding rollers for the covers, a gluing device for applying glue to the inside of said covers, rollers for 125 grooving said covers, a rotating member having movable jaws of which one is serrated along its lower edge and the other is provided with a plate hinged thereto and serrated along its lower edge, a vertically 130

reciprocated device for applying the cover to the block of sheets, movable jaws carried by said device and serrated along their edges, said serrations engaging between the 5 serrations on the jaws of the rotating member, stops for prizing the said movable jaws of the vertically reciprocated device apart shortly before they reach their highest position and as they reach their lowest position, 10 a movable plate mounted between the jaws of said device, means for controlling the movement of said plate consisting of a movable plate mounted on said reciprocating member, bolts mounted on said plate, pins 15 actuating said plate, said bolts engaging the head of said pins, and a projection on said plate and a stop engaged by said projection as the reciprocating member reaches its lowest position whereby said plate is 20 moved so as to release the heads of the said pins, substantially as set forth.

6. A machine of the class described comprising in combination feeding rollers for the covers, a gluing device for applying glue 25 to the inside of said covers, rollers for grooving said covers, a rotating member having movable jaws of which one is serrated along its lower edge and the other is provided with a plate hinged thereto and 30 serrated along its lower edge, a vertically reciprocated device for applying the cover to the block of sheets, movable jaws carried by said device and serrated along their edges, said serrations engaging between the 35 serrations on the jaws of the rotating member, stops for prizing the said movable jaws of the vertically reciprocated device apart shortly before they reach their highest position and as they reach their lowest position, 40 and guide flaps carried by said vertically reciprocated device, consisting of flaps carried by levers pivoted on said device, and a roller mounted on said lever, a stop, said roller engaging said stop as the device 45 reaches its lowest position thereby bringing the flaps into operative position.

7. A machine of the class described comprising in combination feeding rollers for the covers, a gluing device for applying glue 50 to the inside of said covers, consisting of two rollers, a vertically reciprocated glue tank, one of said rollers being in contact with glue

contained in the tank, the glue being transferred to the upper or gluing roller when the tank is in its raised position, rollers for 55 grooving said covers, a rotating member having movable jaws of which one is serrated along its lower edge and the other jaw is provided with a plate hinged thereto, and serrated along its lower edge, a vertically reciprocated device for applying the cover to the block of sheets, movable jaws carried by said device and serrated along their edges, said serrations engaging between the serrations on the jaws of the 60 rotating member, and stops for prizing the said movable jaws of the vertically reciprocated device apart shortly before they reach their highest position and as they reach their lowest position substantially as set 65 forth.

8. A machine of the class described comprising in combination feeding rollers for the covers, a gluing device for applying glue to the inside of said covers, consisting of two rollers, a vertically reciprocating glue tank one of said rollers being in contact with the glue in said tank, the glue being transferred to the upper or gluing roller when the tank is in its raised position, and 75 a spring arranged below said gluing roller for pressing said cover into contact with said roller, rollers for grooving said covers, a rotating member having movable jaws of which one is serrated along its lower edge 80 and the other jaw is provided with a plate hinged thereto and serrated along its lower edge, a vertically reciprocated device for applying the cover to the block of sheets, movable jaws carried by said device and 85 serrated along their edges, said serrations engaging between the serrations on the jaws of the rotating member, and stops for prizing the said movable jaws of the vertically reciprocated device apart shortly before 90 they reach their highest position and as they reach their lowest position, substantially as 95 set forth.

In testimony whereof I have affixed my signature in presence of two witnesses.

AUGUST DWORAK.
